UNITED STATES PATENT OFFICE.

HENRY L. WILCOX, OF GREAT BARRINGTON, MASSACHUSETTS.

BICYCLE-RACK.

SPECIFICATION forming part of Letters Patent No. 620,863, dated March 7, 1899.

Application filed November 1, 1898. Serial No. 695,220. (No model.)

To all whom it may concern:

Be it known that I, HENRY L. WILCOX, of the town of Great Barrington, county of Berkshire, and State of Massachusetts, have invented a new and useful Improvement in Bicycle-Racks, which is fully set forth and described in the following specification, taken in connection with the drawings, which form a part thereof, and in which—

10 Figure 1 is a perspective view of a rack embodying my invention when open; Fig. 2, a side elevation when partially folded; Fig. 3, a front elevation when folded; Fig. 4, a detail view of the hinged portion.

15 In all figures similar letters of reference represent like parts.

My invention relates to an improvement in bicycle-racks, and has for its object the construction of a rack, of wood or other suitable material, which when in use will stand firmly and support without danger of falling a number of bicycles and which when not in use can be easily folded into small compass for shipping or storage.

25 With this end in view my invention consists in a rack having a series of vertical and horizontal rods of sufficient distance apart to receive a bicycle-wheel tire, a bar or rod by which said horizontal rods may be folded in 30 a line with said vertical rods, and in certain other details of construction, as will herein-after be more fully pointed out and described.

As herein shown, the rack comprises base-frames A and B, each frame consisting of end bars or rods a and a' , said bars a' being somewhat shorter than bars a to permit of folding, as hereinafter described. A series of horizontal bars or rods a^2 are adapted to connect end bars a and a' of frames A and B and are secured thereto by insertion in holes in said end bars or in other well-known manner, each of said bars a^2 being separated by spaces, each of which is of sufficient width to receive a bicycle-wheel tire. The bars a' , as shown, are in shape a segment of a circle greater than a semicircle (although circular or other shaped bars may be used without departing from the spirit of the invention) and 45 are provided with grooves or notches b , b' , and b^2 , as shown in Figs. 1, 3, and 4. Hinges C, secured to the under side of the bars a' ,

unite said base-frames A and B, as shown in Fig. 4. A vertical or upright frame D, consisting of a board or bar d and a series of vertical bars or rods d' , secured thereto and corresponding to the bars a^2 when the rack is assembled, is secured to said base-frames A and B by means of braces d^2 , the lower ends of which are adapted to extend beyond the end bars a , to 55 which they are secured in well-known manner, while the other ends of said braces d^2 are pivoted to the board d , as shown in Figs. 1, 2, and 3, the frame D being also further secured by the extension of the bars d' between the 60 grooves b^2 of the bars a' and beyond said bars. A bar d^3 , similar to the bars d' and forming the middle one of said bars d' , is adapted to pass through a vertical perforation in the board D and has secured to its outer end a hook or 70 handle d^4 . The lower end of said bar d^3 is adapted to extend between the grooves b^2 and is pivoted to one of said hinges C, as shown in Fig. 4. The inner surfaces of the board d and bars a are also notched or 75 grooved, so that a bicycle-wheel may more firmly rest therein, while the lower ends of the braces d^2 and bars d' rest on the ground when the rack is open and in use, thus making the rack firm and rigid. 80

When it is desired to fold the rack, the operator draws upon the hook d^4 , which causes the bar d^3 to be drawn upward, thus closing the hinges C and frames A and B by causing the bars a' to slide upward on the bars d , 85 this being permitted by the passage of said bars d' through the grooves b^2 in said bars a' , as shown in Figs. 2 and 3, the operation being reversed when the frame is to be opened for use. 90

Having now described my invention, what I claim, and desire to secure by Letters Patent, is—

1. In a bicycle-rack the combination with a base-frame, consisting of two parts, each 95 part having a series of horizontal bars; of a hinge or hinges uniting said two parts; a vertical frame secured to said base-frame, and means for drawing the inner ends of said base-frame upward on said vertical frame to fold 100 the same, substantially as described.

2. In a bicycle-rack the combination with a base-frame consisting of two parts, each part having a series of horizontal bars; of a

hinge or hinges uniting said two parts; a vertical frame having a series of vertical bars; braces adapted to secure said vertical frame to said base-frame; and an adjustable bar secured to one of said hinges, substantially as described.

3. In a bicycle-rack a base-frame consisting of two sections, secured together at their inner ends by hinges; of a series of grooves in the inner ends of said sections; of a vertical frame consisting of a series of vertical bars, the lower ends of which are adapted to pass through said grooves; and an adjustable ver-

tical bar attached to one of said hinges, said vertical bar being adapted to be raised or lowered to fold or unfold said base-frame, substantially as described.

In witness whereof I have hereunto set my hand, at Great Barrington, in the county of Berkshire, State of Massachusetts, this 27th day of October, 1898.

HENRY L. WILCOX.
